his ATTORNEY.

UNITED STATES PATENT OFFICE.

ROBERT ANDERSON, OF NEW YORK, N. Y.

BRACELET.

1,276,607.

Specification of Letters Patent. Patented Aug. 20, 1918.

Application filed May 23, 1917. Serial No. 170,361.

To all whom it may concern:

Be it known that I, ROBERT ANDERSON, a citizen of the United States, residing at the city of New York, county and State of New York, have invented certain new and useful Improvements in Bracelets, of which the following is a full, clear, and exact specification.

This invention relates to improvements in flexible bracelets, and the same has for its object more particularly to provide a flexible bracelet which will be similar in appearance to the flexible box bracelets now in use, but which will require less material in its construction than is required in the construction of the flexible box bracelets as heretofore made.

Further, the invention has for its object to provide a flexible bracelet of this character, the links of which are more quickly and economically formed than are the box links of the bracelets now in use.

Further, the invention has for its object to provide an improved method of constructing the links and of assembling the same to form the bracelet.

Other objects will in part be obvious and in part be pointed out hereinafter.

To the attainment of the aforesaid objects and ends my invention consists in the novel details of construction, and in the combination, connection and arrangement of parts hereinafter more fully described and then pointed out in the claims.

35 In the accompanying drawing showing an illustrative embodiment of the invention;

Figure 1 is a perspective view of a bracelet constructed according to and embodying the invention;

40 Fig. 2 is a perspective view of the upper side of a blank from which a link is formed;

Fig. 3 is a perspective view showing the other side of the blank;

Fig. 4 is a perspective view of a link formed from the blank shown in Figs. 2 and 3;

Fig. 5 is a bottom or inverted plan view illustrating the manner of assembling the links to form a bracelet; and

50 Fig. 6 is a side elevational view showing the links in their assembled position.

In the flexible box bracelets now in use each link is in the form of an inverted, hollow box comprising a body portion and 55 downwardly extending side walls and end walls. As the end walls of the links are not

exposed to view when the bracelet is worn they do not in any way affect the appearance of the bracelet, but, on the other hand, they increase the cost of the bracelet by an 60 amount equal to the cost of the material of which they are composed. In the bracelet constructed in accordance with the invention as hereinafter described, the links are formed without end walls, thereby effecting 65 a saving in the amount of metal used, and a consequent saving in the cost, without in any way detracting from the appearance of the bracelet.

Referring to the drawing 10 denotes a 70 bracelet formed of a plurality of links 11, and provided with a suitable catch or fastening device to enable it to be placed upon, or removed from, the wrist of wearer. As shown, each of the links 11 has a jewel 12 75 set therein, but it will of course be understood that the jewels 12 may be omitted, if desired, without in any way departing from the spirit of the invention.

Each link 11 is U-shaped or channel-shaped and comprises a body portion 13 having side walls 14 extending downwardly therefrom and at right angles thereto. The lower edges of the side walls 14 are slightly shorter than the upper edges thereof, for a 85 purpose hereinafter described.

At one of the ends of each of the side walls 14, and in the plane thereof, is a round projection 15, and at the other of the ends of each side wall 14 is a similarly 90 shaped recess 16. Adjacent its recessed end each of the side walls 14 is provided with a depressed or offset portion 17, the outer surface of which is in the plane of the inner surface of the side wall 14 and forms a 95 seat 18.

The links 11 are preferably formed in the following manner. By means of a suitable die or punch a blank 19 is punched or stamped from a sheet of metal, which blank 100 19 is provided with projections 15, recesses 16, and offset portions 17 adjacent the ends thereof, as shown in Figs. 2 and 3.

Simultaneously with the stamping of the blank 19 from the sheet of metal, transverse 105 grooves 20 are formed in the under surface thereof, the grooves 20 being spaced from the ends of the blank a distance equal to the desired height of the side walls 14 of the link 11. If the links 11 are to be provided 110 with jewels, a hole 21 is then formed in each blank 19, in any suitable manner, intermedi-

ate the grooves 20. The end portions of each blank 19 are then bent downwardly along the grooves 20 until they assume a position at right angles to the central portion of the blank 19, thereby forming a link as shown in Fig. 4.

In forming the bracelet 10 the requisite number of links 11 are assembled in alignment with one another with the projections 15 of each link 11 resting upon the seats 18 and engaging the recesses 16 of the next adjacent link, as shown in Figs. 5 and 6. While the assembled links 11 are securely held in their aligned position holes are drilled 15 through the projections 15 and the registering offset portions 17 by a suitable drill 22 as indicated in Fig. 5, the holes being drilled preferably first in one side of the links 11 and then in the other side thereof. 20 After the holes have been drilled pins 23 are inserted therethrough, and the ends of the pins 23 are then soldered or otherwise fixedly secured within the holes in the projections 15.

25 As the pins 23 are not fixedly secured within the holes formed in the offset portions 17 of the links 11, and as the inner edges of the side walls 14 are slightly shorter than the outer edges thereof, as above set forth, the links 11 are free to move relatively to one another to permit the bracelet to be placed around and to conform to the curvature of the wrist of the wearer.

When the bracelet is upon the wrist of 35 the wearer it will present the same appearance as is presented by flexible bracelets formed of box-like links such as are now being used, but by reason of the fact that the links 11 of the bracelet above described 40 are not provided with end walls, as are the box links heretofore used, there is a great saving in the amount of material used in forming the links, in consequence of which there is a great saving in the cost of the 45 material entering into the construction thereof. Furthermore, the construction of the U-shaped or channel-shaped links 11 in

the manner above described, is accomplished more easily and quickly and with less expense of labor, than is the case with respect 50 to the box links, whereby the cost of manufacture is still further lessened.

Having thus described my said invention what I claim and desire to secure by Letters Patent is:—

55 1. A flexible bracelet comprising a plurality of links, each of said links comprising a body portion and downwardly extending side walls, each of said side walls being provided with a projection at one of its ends and with a correspondingly shaped recess at the other of its ends, each of said side walls being provided adjacent its recessed end with a seat having its outer surface in the plane of the inner surface of said side 60 wall, the projections on each link engaging the recesses and the seats of the next adjacent link, and connecting means co-acting with the interengaging projections and seats of adjacent links, substantially as 70 specified.

75 2. A flexible bracelet comprising a plurality of links, each of said links comprising a body portion and downwardly extending side walls, each of said side walls being provided with a projection at one of its ends and with a correspondingly shaped recess at the other of its ends, each of said side walls being provided adjacent its recessed end with a depressed portion constituting a seat, the 80 projections on each link engaging the recesses and the seats of the next adjacent link, and connecting means co-acting with the interengaging projections and seats of adjacent links, substantially as 85 specified.

Signed at the city of New York, borough of Manhattan, county of New York, State of New York, the 5th day of May, one thousand nine hundred and seventeen.

ROBERT ANDERSON.
